BLADE AND TOOLHOLDER

Filed April 30, 1948

UNITED STATES PATENT OFFICE

2,605,545

BLADE AND TOOLHOLDER

Joe B. Weems, Dickson, Tenn.

Application April 30, 1948, Serial No. 24,362

1 Claim. (Cl. 30—337)

1

This invention relates to blade and tool holders wherein cutting blades are clamped in the ends of handles, and in particular a holder having a socket in the end for receiving the shank of a blade with locking means for clamping the blade in operative position and also having a blade storage compartment in the opposite end of the holder with a hinged cover and a combination spring for resiliently holding the clamping means and cover.

The purpose of this invention is to provide a unique holder for cutting blades and the like which rigidly clamps the blade and also provides storage space for additional blades.

Various devices have been provided for holding safety razor blades and blades of different types for knives, tools and other devices, and whereas these are satisfactory for average use it is difficult to grip the holder close to the cutting blade for accurate cutting. With this thought in mind this invention contemplates a holder having a cutting blade holding socket in a comparatively small streamlined end and a storage compartment in the opposite end for carrying additional blades.

The object of this invention is, therefore, to provide a holder and handle for relatively small cutting blades in which the holder may be gripped comparatively close to the blade for accurate cutting.

Another object of the invention is to provide a holder for small cutting blades in which a compartment for additional blades is provided.

Another object of the invention is to provide a blade holder in which a shank of a blade is clamped in a socket having an enlarged inner end wherein projections on the shank of the blade secure the blade rigidly in the socket.

A further object of the invention is to provide an improved blade holder having a blade storage compartment therein which is of a simple and economical construction.

With these and other objects and advantages in view the invention consists of the new and useful combination, construction and arrangement of parts as hereinafter more fully described, set forth in the claim appended hereto, and disclosed in the accompanying drawings forming part hereof, wherein:

Figure 1 is a plan view of the holder with the blade omitted.

Figure 2 is a longitudinal section through the holder showing a knife blade extending from the end thereof and with part of the blade broken away.

2

Figure 3 is a view similar to that shown in Figure 2 with part of the handle broken away, the cover of the blade holding compartment open, and the blade released.

Figure 4 is a view looking upward toward the under surface of the cover of the holder with the base removed.

Figure 5 is a plan view of the base of the holder with the cover removed.

Figure 6 is a cross section through the holder taken on line 6—6 of Figure 2.

Figure 7 is a cross section through the holder taken on line 7—7 of Figure 2.

Figure 8 is a cross section through the holder taken on line 8—8 of Figure 2.

Figure 9 is a cross section through the holder taken on line 9—9 of Figure 2.

Figure 10 is a plan view of the combination spring removed from the holder.

Figure 11 is a detail showing the shank of a blade adapted to be clamped in the holder.

Referring now to the drawings wherein like reference characters denote corresponding parts the improved blade holder of this invention includes a base 10, a cover 11, a spring 12, a thumb button 13, and a lever 14.

The base 10 is formed as illustrated in Figures 2 and 5 with a blade holding socket 15 in one end, a blade storage compartment 16 in the other, 30 and a spring holding recess 17 in the intermediate portion. The socket 15 is formed with tapering sides providing a narrow part 18 with an enlarged inner end 19, and a shank 20 of a blade 21 having corresponding tapering sides and an enlarged end 22 fits snugly in the socket. The button 13 which is provided with a knurled outer surface extends through a slot 23 in the cover 11 and a plate 24 on the inner end slides over the shank 20 as the button is moved forward and 40 locks the shank of the blade in the socket, as shown in Figure 2.

The spring recess 17 which is positioned below the button slot 23 is provided with a spring holding shoulder 25, a lug 26, and a partition 27, and 45 the spring 12 is formed with a U-shaped section 28 having converging sides that form a constricted open end, wherein as the U-shaped section snaps over the shoulder 25 the spring will be retained in position. One end 29 of the spring 50 extends under the button 13 urging the button upward, and the other end 30 extends over the lug 26 and bears against the surfaces 31 and 32 of a hub 33 of the lever 14. The lever is pivotally mounted on a pin 34 in an opening 35 in the 55 cover 11, and with the surfaces 31 and 32 posi-

tioned as shown the spring will hold the lever in either the open or closed position.

The cover 11 is secured to the base 10 by screws 36 and 37 at the end in which the blade is positioned and a screw 38 in a recess 39 in the opposite end. The cover 11 is provided with downwardly extending pins 40 and 41 that register with openings 42 and 43 in the base. The cover is also provided with slots 44 and 45 into which the ends of the pin 34 in the hub of the lever 14 extend, as shown in Figure 8.

The outer end of the lever 14 is provided with an arcuate lip 46 that extends over the screw 38, and as shown in Figure 2 the upper surface of the lever is flush with the upper surface of the cover, so that the lever forms a cover for the blade storage compartment 16.

With the parts arranged in this manner the shanks of blades may readily be clamped in the socket 15 and when in position the blades will be rigidly held so that they may be used to cut with accuracy, and as the blades are worn they may readily be replaced with new or sharpened blades from the storage compartment.

It will be understood that modifications may be made in the design and arrangement of the parts without departing from the spirit of the invention.

What is claimed is:

In a blade holding handle, the combination which comprises an elongated base with an enlarged outer hand gripping end and with the sides and lower surface thereof tapering toward an opposite blade holding end, said base having an outer gripping surface and an inner surface having recesses therein, said recesses including a first recess having tapering sides and positioned

in the inner surface of the blade holding end to form a blade holding socket and a second recess adjoining the first recess and adapted to receive a spring, a cover, the shape of which corresponds to that of the base superimposed upon said base and having a slot therethrough, said slot positioned in alignment with and spaced from said blade holding socket, a blade locking plate having an extended button on one end thereof slidably mounted in the cover with the said button positioned in the said slot and with the end opposite to that on which the button is positioned extended over said blade holding socket in the base for clamping the blade in the socket, and a spring in said second recess frictionally holding the said blade locking plate in the position of locking the blade in the socket and with the button extended through the slot of the cover.
